(57) **CLAIM**

The ornamental design for a patient user interface, as shown and described.

DESCRIPTION

FIG. 1 is a front perspective view of a first embodiment of a patient user interface showing our new design;

FIG. 2 is a rear perspective view thereof;

FIG. 3 is a top elevation view thereof;

FIG. 4 is a left elevation view thereof; the right elevation is a mirror image and is not depicted;

FIG. 5 is a bottom elevation view thereof;

FIG. 6 is front elevation view thereof;

FIG. 7 is a rear elevation view thereof;

FIG. 8 is a front perspective view of a second embodiment of a patient user interface;

FIG. 9 is a front elevation view thereof;

FIG. 10 is a rear elevation view thereof; and,

FIG. 11 is a top elevation view thereof.

The broken lines in the drawings depict portions of the patient user interface that form no part of the claimed design.

1 Claim, 5 Drawing Sheets
